(57) **CLAIM**

The ornamental design for a retractable gate, as shown and described.

DESCRIPTION

FIG. 1 is a front, right and top perspective view of a retractable gate, showing my new design;

FIG. 2 is a rear, left and bottom perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof;

FIG. 8 is a bottom plan view thereof;

FIG. 9 is a perspective view of the retractable gate in a detached state;

FIG. 10 is another perspective view thereof in a detached state;

FIG. 11 is an enlarged view of portion 11 of FIG. 1 thereof;

FIG. 12 is an enlarged view of portion 12 of FIG. 1 thereof;

FIG. 13 is an enlarged view of portion 13 of FIG. 1 thereof;

FIG. 14 is an enlarged view of portion 14 of FIG. 2 thereof; and,

FIG. 15 is an enlarged view of portion 15 of FIG. 10 thereof.

The broken lines shown in the drawings illustrate portions of the retractable gate that form no part of the claimed design. The dot-dash broken lines depict the boundaries of the enlargements that form no part of the claimed design.

1 Claim, 15 Drawing Sheets
